US00D528917S

(12) **United States Design Patent** (10) **Patent No.:** **US D528,917 S**
Bertucci et al. (45) **Date of Patent:** **** Sep. 26, 2006**

(54) **BOTTLE**

(75) Inventors: **Michael H. Bertucci**, Gurnee, IL (US);
Reuben Wu, Saffron Walden (GB);
Matthew E. Young, Cambs (GB)

(73) Assignee: **JohnsonDiversey, Inc.**, Sturtevant, WI (US)

(**) Term: **14 Years**

(21) Appl. No.: **29/234,198**

(22) Filed: **Jul. 14, 2005**

Related U.S. Application Data

(60) Continuation of application No. 29/207,579, filed on Jun. 20, 2004, now Pat. No. Des. 514,447, which is a division of application No. 09/151,595, filed on Nov. 8, 2001, now Pat. No. Des. 496,278.
